(57) **CLAIM**

The ornamental design for a gas dispersing plate for a semiconductor manufacturing apparatus, as shown and described.

DESCRIPTION

FIG. 1 is a perspective view of a gas dispersing plate for a semiconductor manufacturing apparatus.

FIG. 2 is a front elevational view of the gas dispersing plate.

FIG. 3 is a rear elevational view of the gas dispersing plate.

FIG. 4 is a left side elevational view of the gas dispersing plate.

FIG. 5 is a right side elevational view of the gas dispersing plate.

FIG. 6 is a top plan view of the gas dispersing plate.

FIG. 7 is a bottom plan view of the gas dispersing plate.

FIG. 8 is a cross-sectional view taken along line 8-8 of FIG. 6; and,

FIG. 9 is an enlarged detail view of FIG. 7.
